UNITED STATES PATENT OFFICE

2,547,079

TRANSMISSION FOR DRILLING MACHINES

Jean Gérentès, Saint-Etienne, France, assignor
to Constructions Electro-Mécaniques de Saint-Etienne, Saint-Etienne, France, a French company

Application April 17, 1948, Serial No. 21,649
In France May 5, 1947

7 Claims. (Cl. 74—424.8)

1

The present invention relates to drilling-machines which have to bore holes in hard and heterogeneous materials, especially minerals.

The portable electric drilling-machines used up to the present in mines and quarries, are of two types. In one, the drill is fed to the work by the workman through pushing axially on the machine; in the other, the drill is fed to the work by a step-up gear device, the machine being mounted on a head-frame.

The second type of drilling-machine mentioned above, is more suitable especially in the case of work in hard or heterogeneous ores and for which a heavy feed pressure is necessary so that the drill can normally carry out the perforating.

This feed pressure is obtained in different ways—either by assembling the drilling-machine on an arm and by feeding it to the work by screw or rack—or else by keeping the drilling-machine fixed, and in making the drill-piece move forward at the same time as the rotary motion is produced.

With the last manner of procedure, the feed movement is given by the driving shaft which at the same time causes the rotary motion of the drill-piece. The feed mechanism is often frictionally-furnished, but the characteristic of this device is to give a fixed travel per turn, whatever be the hardness of the rocks drilled, until the elements of the friction device slips the one on the other or the motor stalls. The axial force to be applied on the drill can become considerable in certain rocks and this fact compels to increase the size and consequently the weight of the members of the machine—so that said machine becomes very uneasy to handle.

The invention has for its object to provide an electric rotary drilling-machine, with variable automatic feed movement, light and therefore easily handled, more particularly intended for mines and quarries.

The invention has more especially for its object to provide a drilling machine which comprises two independent mechanisms, one for the feed movement, and the other for the rotation of the drill-piece, these mechanisms being driven by two separate electric motors, the motor for the feed movement being a motor having a high rotor slip so that the speed of said motor varies with the hardness of the material bored and said mechanisms being combined so that the feed speed is a direct function of the difference between the speeds of said motors.

Owing to these features, the feed of the drill-piece is automatically variable, according to the

2

hardness of the material bored, for said hardness modifies automatically the speed of the corresponding motor; said fact is very important for machines which, having to bore holes which may exceed a depth of two metres, meet with different strata of material of quite different hardness.

Other features of the invention will be apparent from the following description.

On the accompanying drawing, given merely as an example:

Fig. 1 shows a longitudinal section of a drilling-machine according to the invention;

Fig. 2 is a front view thereof;

Fig. 3 is, in section, a detail of embodiment of the nut, causing the displacement of the drill-piece;

Fig. 4 is an electric wiring diagram.

According to the example shown, the machine comprises a casing formed of two parts 1 and 2, joined through the medium of a cheek or cross-piece 3.

In the casing 1 is housed a main electric motor, of which the shaft 5 rotates in ball-bearings 6 and 7; it is provided at the back with a fan 8 intended to create a current of cold air along the sides of the casing of the motor in order to cool them.

In the front, the shaft 5 extends through the cross-piece 3, and ends in the form of a toothed part 9. Said toothed part 9 engages, through the medium of an idle pinion 10, with a toothed crown 11. The pinion 10 is freely centered, on the one hand by means of a ball-bearing 40 on a trunnion 41 integral with the cross-piece 3, and on the other hand by means of another trunnion 42 integral with said pinion 10 in a ball-bearing 43 carried by the part 2 of the casing. The crown 11 comprises a hub, centred by bearings 12 and 12^a in said cross-piece 3 and in a bush 21. In this hub is keyed slidably, according to the axis XX, a screw 13, by grooves 13^a which give to this screw the rotary movement conveyed by the gear train.

On the end of the screw 13 is secured the driving device 14 of the drill-piece. A housing 14^a is provided inside the screw for the centring of the said drill-piece.

The longitudinal displacements of the screw 13 in the direction of the arrow f¹ or in reverse direction, are given to it, independently of the above described mechanism which ensures its rotation, by the following mechanism.

In the casing 2 is placed a second electric auxiliary motor 15. It is constituted by a reversible motor of a well known type enabling a high rotor

slip, that is to say, a motor in which the rotary speed of the rotor can decrease in very big proportions when the resisting torque increases. This motor may be for instance an asynchronous motor having a particularly solid squirrel-cage rotor. The shaft 16 of said motor rotates in the casing 2 and in a cover 17 secured to this casing, drives, through the medium of a pinion 18 keyed on it, and of an intermediary idle pinion 19 centered on the trunnion 42, a toothed crown 20. This crown is keyed on the bushing 21. This bushing, concentric to the screw 13, is centered by the ball-bearings 22 and 23 in the casing 2. These bearings are locked longitudinally by a nut 24.

In the bushing 21 is mounted a nut 25 driven by lugs 26 (Fig. 3) engaging in the notches of the said bushing 21; this nut is locked on the bushing by a check-nut 24a. In this nut 25 is screwed the screw 13.

Fig. 4 shows the electric devices and their connections in the case of feeding by alternating current.

The current collector 28 is a five-plugged one 29, corresponding to three feeding leads 39 and to two pilot leads 31 serving to control the relays which open or cut off the main current (usual relays, not shown, placed in a cabinet apart from the drilling-machine). A control switch 32 placed in the circuit of these leads 31 therefore allows the putting under tension or out of tension of the main leads 30.

The main motor 4 driving in rotation the screw 13, is connected directly to the three leads 30.

On the contrary, the feeding motor 15 is connected to the three leads 30 by a reversible switch of a conventional type with twin keys 33 and contact-studs 34 and 35. In a certain position (keys 33 on the contact-studs 34 for example), the motor 15 turns in the same direction as the main motor and this corresponds to the feeding movement of the tool in the direction of the arrow f¹; in another position, the motor 15 turns in the reverse direction to the main motor and this corresponds to the backward return of the tool.

The machine operates as follows: by closing the control switch 32, the lead 30 is put under tension. The main motor 4, fed, drives in rotary motion the screw 13 through the gear trains 9, 10, 11 and as a result, the drill-piece.

By closing the switch twin keys 33 on the contact-studs 34, the auxiliary motor 15 is fed so that this motor 15 turns in the same direction as the motor 4. The nut 25 is therefore driven in rotation around the axis XX in the same direction as the screw 13, and this at a higher speed than that of the screw, the ratio of the train 18, 19, 20 being lower than the ratio of the train 9, 10, 11. The screw 13 therefore undergoes towards the front a longitudinal displacement whose value depends on the difference between the speeds of the nut and of the screw.

Progressively with the feed movement of the drill-piece in the direction of the arrow f¹, if the materials met with have a variable hardness, there results a corresponding variation of the resistance to the feeding movements and an increase of the resisting torque on the motor 15. This motor, by reason of its high-rotor slip coefficient, slows up, and it is the same with the feeding movement which finds itself stopped when the nut turns at the same speed as the

screw. The feeding thus remains constantly proportional to the difficulty of boring. The pressure on the drill-piece is therefore adjusted automatically, according to the hardness of the rock.

By reversing the switch twin keys 32 on the contact-studs 35, the rotary direction of the auxiliary motor is changed and, as then no resistance is offered to the displacement towards the rear of the screw 13, the motor turns at its highest speed, and there is obtained, by addition of the reverse speeds of the screw 13 and the nut 25, a very quick return axial travel of the drill-piece.

It is advisable to note, moreover, that the arrangement described, in which the members situated around the screw 13 forming a piling-up between the ball-bearing 12 and the nut 24, permits an easy and very quick dismantling and assembly of the different devices.

The nut 25 is easily interchangeable through simply unscrewing the check-nut 24a; this allows an easy adapting of the machine according to the nature of the ground or other heterogeneous material to be drilled, by replacement of the nut 25 and the screw 13 by another set having a different thread.

The invention is naturally not limited to the embodiment shown and described, which has been chosen merely as an example.

Having now described my invention what I claim as new and desire to secure by Letters Patent is:

1. In an electric drilling machine a casing, a screw-threaded shaft projecting at least by one of its ends from said casing in the walls of which it is mounted so as to be able to rotate around and to slide along its own axis, a tool-holder carried by said end outside said casing, a first electro-mechanical driving device located in said casing and comprising a gear member rotatably mounted in said casing and in which said shaft is slidably keyed and an electric motor secured in said casing for imparting to said gear member a rotation and a second electro-mechanical driving device located inside said casing and comprising a nut which is rotatably mounted in said casing so as to be unable to move longitudinally and in which said shaft is screwed and an auxiliary motor having a high rotor slip for driving positively said nut, so that the feeding axial speed and the return axial speed of said shaft are direct functions of the difference between the speeds of rotation imparted by said motors respectively to said shaft and to said nut.

2. An electric drilling machine according to claim 1 wherein said auxiliary motor is a reversible motor and is combined with a control switch disposed in its feeding circuit.

3. An electric drilling machine according to claim 1 wherein said first electro-mechanical driving device comprises said main motor, a pinion secured on the shaft of said motor, an idle intermediate pinion mounted in said casing to rotate freely around its axis which is stationary and said gear member in which the screw shaft is slidably keyed, said idle pinion meshing with said pinion secured on the shaft of said motor and with said gear member.

4. An electric drilling machine according to claim 1 wherein said second electro-mechanical driving device comprises between said auxiliary electric motor and said nut a gear transmission comprising a pinion secured on the shaft of said auxiliary motor, an intermediate idle pinion

mounted in said casing to rotate freely around its axis which is stationary and a toothed bushing rotatably mounted in said casing and in which is keyed said nut, said intermediate idle pinion meshing with said pinion secured on said shaft of the auxiliary motor and with said bushing.

5. An electric drilling machine comprising in combination a casing, a screw-threaded shaft projecting at least by one of its ends from said casing in the walls of which it is mounted so as to be able to rotate around and to slide along its own axis, a tool-holder secured to said end of said shaft, a first electro-mechanical driving device which is located in said casing and comprises a crowned gear member rotatably mounted in said casing and in which said shaft is slidingly keyed, a main electric motor secured to said casing and a first gear train connecting said motor to said crowned gear member, a second electro-mechanical driving device situated inside said casing and comprising a toothed bushing rotatably mounted in said casing so as to be unable to move longitudinally, a nut which is keyed in said bushing and in which said shaft is screwed, an auxiliary reversible electric motor having a high rotor slip and a second gear train connecting said auxiliary motor to said bushing, and a control switch placed in the feeding circuit of said auxiliary motor.

6. An electric drilling machine according to claim 5 wherein the ratio of said first gear train is lower than the ratio of said second gear train and said switch is so arranged that for the feeding drive said nut turns in the same direction as said screw-threaded shaft but quicker than it.

7. An electric drilling machine which comprises in combination a casing formed by a front wall, an intermediate wall and a rear part, assembled together so as to form a front compartment and a rear compartment, said front wall being provided with an aperture and said intermediate wall being provided in said front compartment with a bearing recess, a first ball-bearing centered in said bearing recess, a crowned gear member having a hollow hub formed by axial projections from both faces of said member, one of said projections being centered in said first

ball-bearing, a screw-threaded shaft the longitudinal axis of which coincides with the axis of said hub in which said shaft is slidingly keyed, said shaft projecting at least by one extremity 5 which forms a part of a tool-holder, from said casing through said aperture of said front wall of said casing in the intermediate wall and rear part of which said shaft is mounted so as to be able to rotate around and to slide along its own axis, a second ball-bearing centered on the other projection of said hub, at least a third ball-bearing coaxial to said first and second ball-bearings and secured in said casing in said front compartment, a bushing provided with outer teeth and 10 centered on said first and third ball-bearings, a nut keyed in said bushing and in which said screw-threaded shaft is screwed, a check-nut screwed on said bushing in said aperture of said front wall and abutting said nut to keep said latter in position longitudinally with respect to 15 said bushing, a main electric motor located and secured in said rear compartment, the shaft of said motor protruding into said front compartment through said intermediate wall, a first gear transmission in said front compartment between the front end of said shaft of said main motor and said crowned gear in order to rotate the 20 screw-threaded shaft around its own longitudinal axis, an auxiliary reversible electric motor having a high rotor slip, located and secured in said front compartment, a second transmission gear between said auxiliary motor and said bushing to rotate said nut, and control electric switch placed in the feeding circuit of said auxiliary 25 motor.
